UNITED STATES PATENT OFFICE.

EDMUND HENGELHAUPT, OF CHICAGO, ILLINOIS.

DESIGN FOR A SALT-BOX.

SPECIFICATION forming part of Design No. 37,315, dated January 31, 1905.

Application filed December 28, 1904. Serial No. 238,689. Term of patent 7 years.

To all whom it may concern:

Be it known that I, EDMUND HENGELHAUPT, a citizen of the United States, residing at Chicago, in the county of Cook and State of Illinois, have invented a new, original, and ornamental Design for a Salt-Box, as shown in the accompanying drawing, which is a side elevation thereof.

What I claim as new, and desire to secure by Letters Patent, is—

The ornamental design for a salt-box, as shown.

EDMUND HENGELHAUPT.
